UNITED STATES PATENT OFFICE.

JEROME F. DOWNING, OF ERIE, PENNSYLVANIA.

CARRIER APPARATUS.

SPECIFICATION forming part of Letters Patent No. 328,660, dated October 20, 1885.

Application filed September 12, 1885. Serial No. 176,918. (No model.)

To all whom it may concern:

Be it known that I, JEROME F. DOWNING, a citizen of the United States, residing at Erie, in the county of Erie and State of Pennsylvania, have invented certain new and useful Improvements in Carrier Apparatuses; and I do hereby declare the following to be a full, clear, and exact description of the invention, such as will enable others skilled in the art to which it appertains to make and use the same.

This invention relates to conveyer systems for stores and other like apparatus; and it consists in improvements in the construction of the elevator device, which receives cars from one track, lowers them to the counter, and elevates them to and puts them onto the other track.

My new improvements are shown in the accompanying drawings as applied to the peculiar form of track and other appliances shown in patents previously issued to me; but such an association is not necessary, as my improvements may be used in connection with almost if not quite all conveyer-systems of this class.

My invention is illustrated in the accompanying drawings, as follows:

Figure 1 is a perspective view of a station on a line of track. A is the track which grades to the central station. B is the track which 30 grades from the central station to the way-station. B' is the receiving-switch track at the way-station. A' is the dispatching-switch at the way-station. C is the elevator way or guide. D is the section of track attached to the elevator. D' is a crank-arm supporting the track-section D. E and E' is the elevator-frame proper. F is a catch for stopping the elevator at the point to receive a car from the receiving-switch, and F' is a cord for drawing back 40 the catch F.

Fig. 2 is a perspective view of the elevator-way C, the elevator-frame E E', the track-section D, and its support D', the elevator-way being broken out to show the contained parts 45 clearly.

It will be seen from these figures that the elevator-way is a tube having a slot, C', throughout its length, or as much thereof as is necessary to give the proper vertical movement, and 50 that the elevator-frame consists of a piston, E, within the tube, and an arm, E', extending out through the slot C'. The track-section D,

or any other form of car receiving and supporting device, is supported by the arm E'. By constructing the elevator-way in this manner it can serve as a supporting-post to sustain the tracks. So far as I am aware all conveyer-system elevator-ways, when composed of a single rod, are clasped by the elevator-frame, and consequently cannot be utilized to support the tracks, and therefore other means for supporting the tracks must be provided. It will be seen that the arms c c', which support the tracks A A' and B B', spring from ferrules on the elevator-way, and when required the ferrule is slotted to correspond with the slot in the elevator-way. The catch F is pivoted on a ferrule which is slotted, as above described. It is kept up by a spring, f, and can be pulled down by the cord F'. It 65 is placed in proper position to support the elevator at the proper place to bring the track B' and the section of track B' and the section of track D in conjunction. When a car is received and is to be let down to the counter, the cord F' is pulled, and the catch is drawn from under the arm E'.

What I claim as new is—

1. In a conveyer system, the combination, with the receiving and dispatching tracks, of 80 an elevator-way which consists of a vertically-slotted tube arranged with relation to said tracks, substantially as set forth.

2. In a conveyer system, the combination, with the receiving and dispatching tracks, of 85 an elevator-way, which supports said tracks, and is tubular and vertically slotted, and receives within its slot and bore the elevator-frame, substantially as set forth.

3. In a conveyer system, the combination, 90 substantially as herein set forth, of the tracks A A' and B B', the vertically-slotted hollow post C, the arms c c' and c c', secured to said post and supporting said tracks, and the elevator-frame E E', sliding within said post. 95

4. In a conveyer apparatus, the combination, substantially as set forth, of the vertically-slotted hollow post C, the switch-tracks A' and B', the arms c' and c', secured to said post and supporting said switch-tracks, and the elevator-frame E E', sliding in the bore and slot of said post and supporting the track-section D. 100

5. In a conveyer apparatus, the combina-

tion, substantially as set forth, of the switch-tracks A' and B', the vertically-slotted hollow post C, the arms c' c', secured to said post and supporting said switch-tracks, an elevator sliding within the bore and slot of said post, and a catch device supported on said post and adapted, as shown, to support the elevator opposite the receiving-switch B'.

In testimony whereof I affix my signature in presence of two witnesses.

J. F. DOWNING.
